FLUID ACTUATED INTEGRATOR

Emory Frank Stover, Wynnewood, Pa.

Application November 26, 1945, Serial No. 630,909

5 Claims. (Cl. 73—206)

1

This invention relates to integrators and more specifically to apparatus for continuously integrating a variable quantity, such as the pressure of a fluid, to be measured.

This invention further relates to apparatus for integrating quantities which are directly proportional to the measured quantity or which are proportional to the square root of the measured quantity.

The apparatus of the present invention also contemplates alternative operation, as desired, for integration in accordance with the characteristics of the quantity to be integrated.

The apparatus of the present invention also contemplates the utilization of a separate source of fluid under pressure, with the pressure from the source controlled by a quantity, such as fluid under pressure, determined by another variable.

The nature and characteristic features of the invention will be more readily understood from the following description, taken in connection with the accompanying drawings forming part hereof, in which:

Figure 1 is a sectional view of the integrator, taken approximately on the line 1—1 of Figure 2, and showing a preferred embodiment of the invention;

Figure 2 is a front elevational view of the integrator shown in Figure 1, parts being broken away to show the details of construction;

Figure 3 is a fragmentary sectional view taken approximately on the line 3—3 of Figure 1 and showing certain details of the yoke; and

Figure 4 is a fragmentary sectional view enlarged, taken approximately on the line 4—4 of Figure 2.

It should, of course, be understood that the description and drawings herein are illustrative merely, and that various modifications and changes may be made in the structure disclosed without departing from the spirit of the invention.

Referring more particularly to the drawings, in the particular embodiment of the invention illustrated, a casing 10 is provided, consisting of a front end plate 11, a rear end plate 12 and a cylindrical wall 13 secured together in fluid tight relationship such as by screws 14 and 15.

The front end plate 11 has a flexible metallic bellows 16 secured thereto in fluid tight relationship. The rear end of the bellows 16 is closed by a plate 17 to provide a chamber 18.

The rear end plate 12 has a flexible metallic bellows 20 secured thereto in fluid tight relationship. The bellows 20 is preferably of the

2

same effective area as the bellows 16. If desired a flange 21 on the bellows 20 may be clamped between the end plate 12 and the cylindrical wall 13. The front end of the bellows 20 is closed by a plate 22 to provide a chamber 23. The space within the cylindrical wall 13 and outside the bellows 16 and 20 provides a chamber 24.

The bellows plates 17 and 22 are preferably rigidly connected by a yoke 25 for simultaneous movement thereof.

A fluid connection 26 is provided, in communication with the interior of the chamber 23 for the application in the chamber 23 of a variable fluid pressure. This variable fluid pressure may be an indicating pressure or a pressure transmitted from a meter or from any other desired source corresponding to the quantity to be integrated, the integrator being particularly adapted for use as a remotely located integrating device functioning in connection with first power pressures from any suitable source such as a flow meter.

A fluid connection 27 is provided, preferably connected to a suitable source of pressure fluid, and the fluid connection 27 includes a supply pipe 28 extending within the chamber 24 and within the yoke 25. The supply pipe 28 preferably has a port 29. The yoke 25 carries a needle valve 30, which by its positioning with respect to the port 29, controls the pressure of the fluid supplied to the chamber 24.

In order to provide the desired zero setting, a spring 31 is mounted within the bellows 20 and bears at one end against a spring abutment 32 carried by the interior of the plate 22 and at the other end on a spring abutment 33 carried by an adjusting screw 34 mounted in the rear end plate 12. The adjusting screw 34 is covered in any desired manner, such as by a cap 35, to prevent fluid leakage.

The front end plate 11 preferably has mounted therein a laminar flow tube 36, of predetermined effective length, the inner end of which is in communication with the interior of the chamber 18 and the outer end of which is adapted to discharge against an anemometer wheel 37 for actuation thereof, as hereinafter explained.

A passageway 38 is provided, preferably in the end plate 11, between the laminar flow tube 36 and the chamber 18, terminating, at the laminar flow tube 36, at an opening or gap 39.

Another tube 40 is provided, having a nozzle 41 at the outer or front end thereof, in communication with the interior of the chamber 24,

and with the nozzle 41 disposed to discharge against the anemometer wheel 37.

In order to adapt the apparatus for integration of a variable which is a first or second power function of the quantity to be measured, by selection of the tube 36 or the tube 40, a cap 42 is provided for covering and closing off either of these tubes as desired.

The anemometer wheel 37 is preferably mounted on a shaft 43, which may be journaled at one end in the front end plate 11 and at the other end in a bracket 44 which is mounted on the end plate 11. The shaft 43 is connected by suitable gearing 45 to a counter 46 having visible indicia 47.

The mode of operation will now be explained. Assume first that the tube 40 is closed off by the cap 42 and that the tube 36 discharges fluid against the wheel 37.

Fluid is supplied through the fluid connection 27 and the supply pipe 28 to the chamber 24 at a pressure in accordance with the positioning of the needle valve 30 with respect to the port 29. The needle valve 30 is controlled by the pressures effective in the chambers 18 and 23 on the bellows 16 and 20. The variable or reference pressure is effective in the chamber 23 and an increase thereof tends to move the needle valve 30 to increase the pressure effective in the chamber 24. The pressure prevailing in the laminar flow tube 36 at the gap 39 under steady state conditions, is the same as that in the chamber 18 in the interior of the bellows 16, and in opposition to the pressure in the chamber 23. As a transient condition, during change of pressure in chamber 23, fluid will flow through passageway 38 until the pressures are equalized in chamber 18 and at the gap 39. Fluid is also discharged through the laminar flow tube 36 against the anemometer wheel 37 for actuating the same.

In laminar flow all fluid particles move in parallel lines without crosswise mixing, and the pressure loss or drop due to friction is directly proportional to the first power of the average velocity in the cross section of the tube. Thus, the velocity of the jet discharged from the laminar flow tube 36 and the speed of the wheel 37 are proportional to first power of the fluid pressure effective in the chamber 23.

Upon a change in the pressure in the chamber 23 the needle valve 30 is positioned in accordance with the change to vary the pressures effective in the chamber 24 and in the chamber 18 together with the flow in the laminar flow tube 36. The pressure in the chamber 18 is thus increased or decreased in accordance with the change in the chamber 23 until the pressure in the chambers 18 and 23 are equal as before.

The peripheral speed of the wheel 37 is then proportional to the pressure effective in the chamber 23 and this, as heretofore stated, is proportional to the quantity to be measured. The revolutions of the anemometer wheel 37 are shown by the indicia of the counter. Accordingly, if the quantity to be measured is represented by q , then the accumulated count on the counter 20 equals $fqdt$.

Assume now that the cap is removed from the outer end of the tube 40 and is placed on the outer end of the laminar flow tube 36, so as to permit fluid to discharge from the tube against the anemometer wheel 37 and to prevent discharge from the laminar flow tube 36. The velocity of the fluid discharged through the tube

40 is proportional to the square root of the pressure in the chamber 23.

Upon a change in the pressure in the chamber 23 the needle valve 30 is positioned to vary the pressures effective in the chamber 24 and in the chamber 18. The pressure in the chamber 24 is effective for determining the velocity of discharge through the tube and against the anemometer wheel 37. The velocity of the jet from the tube 40 is thus proportional to the square root of the variable or reference pressure effective in the chamber 23.

I claim:

1. In an integrator, a connection to a source of pressure fluid, a chamber with which said connection is in communication, means responsive to a variable quantity to be integrated, valve means controlled by said responsive means for controlling the pressure of the fluid from said connection to said chamber, a laminar flow tube having one end in communication with said chamber for the discharge of fluid therefrom in jet form at a velocity proportional to the first power of the variable quantity, and counter means

20 including a movable member aligned with the discharge end of said tube.

2. In an integrator, a connection to a source of pressure fluid, a chamber with which said connection is in communication, means responsive to a variable quantity to be integrated, valve

30 means controlled by said responsive means for controlling the pressure of the fluid supplied from said connection to said chamber, a laminar flow tube having one end in communication with said chamber for the discharge of fluid therefrom, a fluid connection in communication with said tube intermediate the ends thereof for applying a pressure on said responsive means in opposition to the force applied by said variable quantity, and

40 counter means actuated by the discharge from said tube.

3. In an integrator, a casing having a chamber therein an expansible chamber member in said casing, a connection to a source of pressure fluid in communication with said chamber, valve

45 means controlled by said expansible chamber member and controlling the supplying of fluid from said connection to said chamber, means for applying a variable to be integrated against said

50 expansible chamber member, a laminar flow tube having one end in communication with said chamber for the discharge of fluid from said chamber in jet form at a velocity proportional to the first power of said variable, a movable member

55 in the path of the jet from said tube and counting mechanism actuated by said movable member.

4. In an integrator, a casing having a chamber therein, an expansible chamber member in

60 said casing, a second expansible chamber member in said casing connected to said first expansible chamber member for movement therewith, a connection to a source of pressure fluid in communication with said chamber, valve means controlled by said expansible chamber members

65 and controlling the fluid from said connection to said chamber, means for applying a variable pressure to be integrated against said first expansible chamber member, a laminar flow tube

70 having its inlet end in communication with said chamber for the discharge of fluid therefrom, a fluid connection from said laminar flow tube intermediate the ends thereof to said second expansible chamber member for applying fluid

75 against said second expansible chamber member,

and means including counting mechanism actuated by the discharge of fluid from said laminar flow tube.

5. In an integrator, a casing having a chamber therein, an expansible chamber member in said casing, a second expansible chamber member in said casing connected to said first expansible chamber member for movement therewith a connection to a source of pressure fluid in communication with said chamber, valve means controlled by said expansible chamber members and controlling the fluid from said connection to said chamber, means for applying a variable pressure to be integrated against said first expansible chamber member, a laminar flow tube having its inlet end in communication with said chamber for the discharge of fluid therefrom at a velocity proportional to the first power of the variable quantity, a fluid connection from said laminar

flow tube intermediate the ends thereof to said second expansible chamber member for applying fluid against said second expansible chamber member to position said members at equilibrium positions, and means including counting mechanism actuated by the discharge of fluid from said laminar flow tube.
